UNITED STATES PATENT OFFICE.

CLARENCE L. HEALY, OF BROOKLYN, ASSIGNOR TO STEPHEN D. FIELD, OF YONKERS, N. Y.

TRANSMITTER FOR PRINTING-TELEGRAPHS.

SPECIFICATION forming part of Letters Patent No. 330,239, dated November 10, 1885.

Application filed June 12, 1885. Serial No. 168,487. (No model.)

To all whom it may concern:

Be it known that I, CLARENCE L. HEALY, of Brooklyn, in the county of Kings and State of New York, have invented certain new and 5 useful Improvements in Printing-Telegraphs, of which the following is a full, clear, and exact description, and will enable those skilled in the art to which they refer to make and use the same.

10 The invention relates to those printing-telegraph systems in which the printing-instruments are located at the various places where news or reports are to be delivered, and which are simultaneously worked by a transmitting apparatus located at a central office, from which radiate lines connecting the various printers with the common transmitter. This transmitting apparatus generally consists of a key-board arranged in combination with 15 and controlling one or more commutator devices, connected with a battery or other source of electricity and with the lines running from the central office, the arrangement being such that by the revolution of the commutator or 20 of some shaft or other device operating it the proper currents are sent out to work the printers in such lines. The commutator or other connected device, as called into action by the transmitting-operator at the key-board, 25 is alternately stopped and started, and this is usually done by a detent device arranged to engage with teeth or stops on some revolving part of the mechanism, which mechanism is usually operated by a continuously-driven 30 friction connection which acts upon the commutator-shaft so as to constantly tend to keep it moving, so that said shaft when released will start off at practically the same rate of speed at which it is at any time driven. As 35 the commutator is driven at a high rate of speed, abruptly arresting it results in sudden and forcible blows being struck by the stops upon its shaft against the detent brought into their path, and the jar or vibration thus produced not only causes a noisy clatter of the 40 parts and their rapid wear, but more particularly it interferes with the certain action of the arresting mechanism, and thus prevents the attainment of the highest speed.

45 50 It is the object of the present invention to

provide the transmitter of a printing-telegraph apparatus with an arresting mechanism that shall act to stop the commutator-shaft, or some like device operating the commutator, with little noise and with the least strain and 55 jar upon the transmitting machinery, and that shall also act with such positiveness and certainty as to permit a higher speed of the commutator than has heretofore been found practically possible.

60 The invention consists, first, in the use of a dash-pot-cushioning device in connection with the mechanism that is used to arrest the shaft operating the commutator, whether such shaft be stopped by the use of a device engaging it positively or by frictional contact, the effect of the cushion being to take up the 65 shock that is produced by the impact of the arresting device upon the revolving parts without causing any back-action, and thereby 70 protect the other parts of the mechanism from undue strain and vibration.

The invention also consists in the combination of a friction mechanism, by means of which the revolving parts may be gradually 75 retarded, with a positive detent for wholly stopping such revolving parts when their speed has been diminished by the friction mechanism.

80 The drawings show various views of a commutator-shaft, or the shaft of a brush or other part that operates a commutator mechanism, Figure 1 being an elevation view in partial section of a detent device and a friction device independently acting upon the same shaft; Fig. 85 2, a plan view of the same; Fig. 3, an elevation view in partial section of a detent and a friction device mounted on a common armature-arm, and Fig. 4 a plan view of the same.

90 Referring to these views in detail, A represents the shaft by which the commutator is operated, this shaft being driven by any suitable power, preferably, however, through the medium of frictional connections, so that the shaft may be stopped at any point by overcoming the power of such connection, and may be caused to start at the same speed as the said connection when released. B is a toothed wheel fixed to the shaft, and C is a dog or detent for engaging said toothed wheel, this detent 95 100

being carried on the piston-rod D, which runs lengthwise through the arm E to the piston F in the cylindrical head G on the end of the arm, such arm being pivoted to suitable standards, 5 and having attached to it the armature H of the electro-magnet I. A spring, J, upon the piston-rod serves to keep the detent and piston at their proper forward position, and a valve, K, acts to admit air behind the piston when 10 it is drawn forward, it being understood that this piston fits nearly air-tight in the head G, so that the air in the head will be held confined and will not instantly escape when the piston is quickly moved inward.

15 The electro-magnet is connected with the key-board of the transmitter, so as to be under the control of the operator. When this magnet is brought into action to arrest the commutator and the detent engages one of 20 the teeth on its shaft, the blow struck by the rapidly and powerfully moving tooth-wheel against the detent is received by the air in the piston-head, this air being compressed by the piston before it can escape and thus made to 25 act as a cushion, so that the standards of the armature-arm are thereby relieved in great part of the pounding or jarring effects that would be produced were the detent unyielding.

30 It is intended that the air-cushion shall receive practically the whole effect of the blow, the spring on the piston being comparatively weak, and being only used to move the piston forward after the tooth-wheel is released. So, 35 too, it is intended that the air forming the cushion shall not be so closely confined, but that upon receiving the blow and absorbing the shock produced by it such air will escape from the piston-head, and so will not react 40 upon the piston, the action being like that of a dash-pot—that is, the elasticity of the air-cushion is expended by resisting the blow, and there is no recoil of the commutator-shaft, as 45 no backward pressure is exerted by the cushioning-piston after the shaft has been arrested.

50 By the use of a yielding stop or detent to arrest the commutator not only is the transmitter protected against undue jar and wear, but the action of the detent is made more certain, and a greater speed of the commutator 55 may be had. With an unyielding or recoiling detent the sudden blows struck against it by the rapidly-revolving teeth on the shaft often act to throw it out of engagement with such teeth, whereas such effect is prevented by using a detent that has the capacity of yielding slightly when struck, but without recoiling, as this action will prevent it from slipping or bounding off, and thus losing its hold 60 upon the tooth-wheel.

65 I am aware that detents have been used for this purpose that were slightly elastic from having been made of spring metal formed into a shape permitting the engaging end to spring back when struck by the revolving stops; but this is not my invention, as such spring-detents exert a backward and yielding pressure

upon the shaft after it has been stopped, as above described.

The letter L indicates another armature-arm 70 that is operated by the electro-magnet M, and carries the friction-pulley N, arranged so as to be brought into close contact with the edge of the friction-disk O on the armature-shaft. To the shaft of this pulley is attached the cord 75 or wire P, which is fastened to the rod Q of the piston R, arranged in the fixed head S after the manner of the cushioning-piston on the detent-arm. When the magnet of this friction device is operated, the friction-pulley is 80 brought into close contact with the friction-disk, and is caused to make a partial revolution, which winds the cord or wire around the pulley-shaft and draws the piston slightly into 85 its head, thereby causing an air-cushion that gradually takes up the strain and jar due to arresting the commutator. By using a pulley, as shown, the wearing away of the two friction-surfaces, and consequent irregular action of the parts, is obviated, for it is intended that the 90 friction-surfaces shall not slip upon each other, but simply revolve together, the force necessary to hold them in unbroken contact when the strain of stopping the commutator is thrown upon a yielding cushion being much less and 95 hence more certain than would be necessary to accomplish the same end without such cushion.

100 It is plain that the action of the friction device for arresting the commutator is less abrupt than that of the positive detent above described, and while it may be used to bring the commutator gradually to a stop, yet it cannot be relied upon to stop it at any exact point with the same certainty as the positive 105 detent. It is believed that the best results will be attained by the conjoint use of these 110 two means, the friction device being used to gradually reduce the speed of the commutator-shaft and the positive detent being then brought into action to completely arrest the 115 revolution of the shaft at the desired point. In this way great speed and accuracy may be attained with a minimum of strain upon the working parts.

120 Two ways of combining these devices are illustrated in the drawings. Figs. 1 and 2 show them as separately mounted, but arranged to act conjointly upon the same shaft, it being understood that the two electro-magnets are so connected with the transmitter key-board that the friction device is first caused to engage with the shaft to reduce its speed, and then the detent acts to positively arrest it and hold it at the point desired. 125 Figs. 3 and 4 show both of these devices mounted upon one armature-arm and operated by a single magnet. It is usual with the detent device to cause it to close upon the tooth-wheel immediately upon a tooth passing the detent, or where these points are, as seen in Fig. 3, and this is for the purpose of bringing the detent down fully into the space in front of a tooth. When, therefore, the armature-

arm carries both arresting devices, provision must be made for the downward movement of the arm after the friction device has been brought into operation, and this is accomplished by placing the pivot of the pulley a little eccentric to its periphery. The action of the combined form of arresting device, as shown in Figs. 3 and 4, then, is this: As the arm is drawn down the friction-pulley is brought firmly against the friction-disk and begins to revolve and at the same time to retard the commutator-shaft; but as the pulley turns its eccentricity permits the arm to be gradually drawn farther down until, when the shaft has been sufficiently retarded, it meets the more positive obstruction afforded by the detent and is fully arrested. When the action of the magnet ceases, the arm is at once drawn back by a suitable spring, and the shaft is started off at the same speed as the friction-connection constantly acting upon it.

In the case of the conjoint use of the arresting devices, the object of the invention will be in large measure attained if the detent be not yielding; but it may have the capacity of yielding somewhat, so as to obviate the jar and strain as far as possible.

I am aware that this apparatus is susceptible of various modifications, and particularly that other cushioning gases or fluids may be used to accomplish the same end, and I would have it understood that I regard all such modifications as the equivalents of the forms here shown and described.

By the shaft herein described as the "commutator-shaft" is meant a shaft which actually carries the commutator or some of the

parts of the commutator, or that is in any way connected with the commutator mechanism so as to revolve therewith.

What is claimed as new is—

1. In combination, in the transmitting mechanism of a printing-telegraph, a revolving commutator-shaft, a device for arresting said shaft, and an electro-magnet for bringing such device into action, and a dash-pot-cushioning device for relieving the mechanism from shock. 40

2. In combination, in the transmitting mechanism of a printing-telegraph, a friction device arranged to gradually reduce the speed of the commutator-shaft, an electro-magnet for bringing such friction device into action so as to operate upon said shaft, and a detent for arresting said shaft when its speed has been reduced by the friction device. 50

3. In combination, in the transmitting mechanism of a printing-telegraph, the commutator-shaft A, provided with teeth or stops B, the yielding detent mechanism C D F G, mounted upon the armature-arm E, and the electro-magnet I, for operating said detent, as and for the purpose set forth. 55

4. In combination, in the transmitting mechanism of a printing-telegraph, the commutator-shaft H, the pulley N, attached to the armature of an electro-magnet, a cushioning device arranged to resist the revolution of said pulley, and a detent for positively arresting the shaft by engaging with teeth or stops thereon, as and for the purpose set forth. 65
